UNITED STATES PATENT OFFICE.

GEORGE S. ARMSTRONG, OF DENVER, COLORADO, ASSIGNOR OF ONE-HALF
TO JULIA E. KIEFER AND WILLIAM G. HUTCHISON, BOTH OF SAME
PLACE.

AMALGAMATOR.

SPECIFICATION forming part of Letters Patent No. 349,778, dated September 28, 1886.

Application filed December 29, 1885. Serial No. 187,027. (No model.)

To all whom it may concern:

Be it known that I, GEORGE S. ARMSTRONG, a subject of the Queen of Great Britain, residing at Denver, in the county of Arapahoe and State of Colorado, and having declared my intention to become a citizen of the United States, have invented a new and useful Improvement in Amalgamators, of which the following is a specification, reference being had 5 to the accompanying drawings, in which similar letters refer to corresponding parts.

The object of my improvement is to provide an amalgamator simple in construction and perfect in its work, which machine may be used alone or in combination with my improved concentrator for which I have obtained Letters Patent of the United States, numbered 327,915, and bearing date October 6, A. D. 15 1885.

In the drawings, Figure 1 is an elevated section of my improved amalgamator, showing the same attached to my concentrator, also showing the propelling mechanism. Fig. 2 is 20 a top view of the propelling mechanism. Fig. 3 is a crank-wheel forming part of the propelling mechanism. Fig. 4 is a top view of an attachment for crank-wheel shown in Fig. 3. Fig. 5 is a side elevation of my improved amalgamator, showing the same attached to my concentrator. The propelling mechanism is not shown in this figure. Fig. 6 is a front 25 end view of my improved amalgamator without the propelling mechanism. Fig. 7 is a rear end view of the same, the door of box A being open. Fig. 8 is a top view of the amalgamating-box.

A is a vertical box with a journal, a , in its center upon each of two opposite sides, by 30 means of which journals the box is mounted upon a suitable frame, B. The journals a work in center boxes, a' , said center boxes having a slight horizontal movement within slotted boxes a'' . The movement of center 35 boxes, a' , within the boxes a'' is controlled by adjusting-bolt a^3 . The boxes a'' are attached to the top of frame B, as shown in the drawings.

Supported within box A and near its bottom is the copper plate f , coated with mercury, 50 the same being placed obliquely within box A, as shown in Fig. 1. Plate f contains receptacles f' and f'' , which are also lined with copper and coated with mercury. Receptacle f'' contains ruffles f^3 . 55

g is an amalgamating-box, to each side of which is riveted a bracket, g' .

To each side of box A is riveted or bolted a plate, a^5 . Brackets g' are attached to plates a^5 by means of rod g^2 , as shown. By this 60 means the rear end of amalgamating-box g is attached to box A. The front end of amalgamating-box g is supported by a rod, h , on each side, which is pivoted to box g at one extremity and bolted to the frame B at the other 65 extremity. Rod h may be so adjusted where it is attached to frame B as to give amalgamating-box g any desired inclination.

Within amalgamating-box g is placed the screen i , containing the riffle i' . Running 70 crosswise of the bottom of amalgamating-box g are the ruffles g^3 . Box g also contains receptacles j and j' . Receptacle j contains the ruffles j^2 . Amalgamating-box g is lined with copper, said lining being coated with mercury. 75

My improved amalgamator is operated by means of the propelling mechanism shown in Figs. 1, 2, 3, and 4. l is a driving-pulley, to which a belt may be attached communicating with any suitable motor. Pulley l is attached 80 to shaft m , to which shaft gear-wheel n is also attached. Shaft m is journaled within suitable journal-boxes, m' , attached to the frame of the machine, as shown. Gear-wheel n meshes within a smaller gear-wheel, n' , attached to 85 shaft p . To shaft p is also attached fly-wheel q and crank-wheel r . Shaft p is attached to the frame of the machine and held in position by journal-boxes p' . The construction of crank-wheel r is shown in Figs. 3 and 4. r' is an adjustable plate pivoted to the wheel at the point r^2 . r^3 is a curved slot, formed within wheel r , and by means of which slot plate r' is adjusted so as to bring crank r^4 at any desired distance from the center of the wheel. Plate r' , when 90 properly adjusted, is held in position by set-

screw r^5 . To crank r^4 is attached pitman-rod s , which rod is attached to box A, as shown. Power being applied to pulley l , the propelling mechanism is set in motion, thus imparting an oscillatory movement to box A. Box A has another motion given by the horizontal movement of boxes a' within boxes a^2 , as before described. The motions of box A are communicated to amalgamating-box g , which will be readily observed. The material to be treated, together with the water required for the purpose, is discharged upon plate f .

When used in connection with my improved concentrator, the material passes directly from the last rifled plate of the concentrator to plate f of the amalgamator. When the amalgamator is used alone, box A contains no rifled plates, and the material is discharged into the top of box A, falling directly upon plate f of my improved amalgamator.

By reason of the combined oscillatory and horizontal movement of box A, as above described, the heavier and coarser particles of precious metal discharged upon plate f are retained within receptacles f' and f^2 , where they form an amalgam with the mercury, while the lighter particles of gold or silver with the crude material are discharged from plate f into amalgamating-box g , first coming in contact with screen i , back of riffle i' . The object of riffle i' is to retain the material so discharged upon the rear portion of said screen until the greater part of the precious metal has passed through the screen into receptacle j' beneath. By virtue of the motion of amalgamating-box g the heavier particles of precious metal have a tendency to remain in the rear portion of box g , while the lightest particles of valuable metal, together with the crude material, pass over riffle i' and pass toward the forward extremity of the box, the precious metal passing through the screen during this process into the bottom of box g , where it is retained by riffles g^3 and receptacle j , forming an amalgam with the mercury with which the copper lining of box g is coated, as aforesaid, while the crude material is discharged from the forward extremity of box g , having been first deprived of all its valuable metal, in the manner described. My improved amalgamator may be attached to my improved concentrator patented as aforesaid, or box A may contain only plate f , with which the material to be treated first comes in contact. Box A may be dispensed with and a suitable frame substituted therefor, to which frame pitman-rod s and amalgamating-box g must be

attached, as described, the object being to form a suitable medium of communicating the motion of the propelling mechanism to box g . This frame of box, whichever is used, should be journaled as box A, herein described, and should also be fashioned to receive plate f in its lower portion, as shown.

The propelling mechanism is the same as that used in my improved concentrator, and I therefore claim nothing on the same except in combination with the other elements of my amalgamator.

Box A contains a door, b , which may be opened for the purpose of cleaning plate f or removing the amalgam therefrom. Door b may be opened or taken out by removing keys b' , there being one on each side.

Amalgamating-box g contains a door, c , in its rear end, which opens downward, giving free access to receptacle j' when it is desired to remove the amalgam therefrom.

What I claim as my invention, and desire to secure by Letters Patent, is—

1. In an amalgamator, the combination of amalgamating-box g , provided with receptacles j and j' , riffles g^3 , screen i , provided with riffle i' and door e , said box being supported by rods h and brackets g' , a suitable frame provided with boxes a^2 and a' , box A, provided with journals a , and mechanism for operating the machine, consisting of gear-wheels n and n' , shaft p , crank-wheel r , and pitman-rod s , substantially as described.

2. In an amalgamator, the combination of a supporting-frame provided with journal-boxes, box A, plate f , containing receptacles f' and f^2 , amalgamating-box g , provided with screen i , receptacles j and j' , and riffles g^3 , box g being attached to box A, and supported by adjusting-rods h , and mechanism for operating the machine, consisting of gear-wheels n and n' , crank-wheel r , shaft p , and pitman-rod s , substantially as described.

3. In an amalgamator, the combination of a supporting-frame provided with boxes a' and a^2 , box A, provided with journals a , plate f , provided with receptacles f' and f^2 , amalgamating-box g , provided with screen i , receptacles j and j' , riffles g^3 , and door c , box g being attached to box A, and supported by adjusting-rods h , and suitable mechanism for operating the machine, substantially as described.

GEORGE S. ARMSTRONG.
